UNITED STATES PATENT OFFICE

GEORGE D. KILBERRY, OF DOWNTON, PENNSYLVANIA, ASSIGNEE, BY MESNE
ASSIGNMENTS, TO BELOIT IRON WORKS, OF BELOIT, WISCONSIN, A CORPORATION
OF WISCONSIN

FOURDRINIER MACHINE

Application filed December 2, 1926. Serial No. 152,174.

My invention relates to paper machinery, having particular relation to those parts which are directly associated with the wire.

One object of my invention is to provide 5 a Fourdrinier part comprising independently removable table-roll and suction-box sections. Such construction permits the replacement of the wire in one-third the time heretofore considered practical and with 10 a corresponding decrease in maintenance charges. It also makes possible the removal of the structure by hand, thereby eliminating the necessity for the expensive power-actuating mechanism embodied in the prior 15 art machines.

Another object of my invention is to provide apparatus of the class described, wherein the removable Fourdrinier part may be lowered from an upper working position to 20 a lower position in engagement with means adapted to facilitate the removal of said part.

A further object of my invention is to provide power means for raising and lowering the Fourdrinier part between the working 25 and removing positions, the power means also serving to operate the couch roll longitudinally of the Fourdrinier part, so that the wire may be draped in place to give ample clearance for inserting the removable parts 30 without injury to the wire.

A still further object of my invention is to provide a Fourdrinier part comprising hinged sections adapted to cooperate with a wire, and power means whereby the pitch 35 of said wire may be adjusted at an intermediate point.

A still further object of my invention is to provide a bodily movable Fourdrinier part 40 characterized by maximum vibration at the breast roll end thereof.

With these and other objects and applications in mind, my invention further consists in the details of construction and operation and arrangement, hereinafter described 45 and claimed and illustrated in the accompanying drawing, wherein

Fig. 1 is a side elevational view of a paper making machine embodying my invention; 50 Fig. 2 is a similar view but showing one

of the positions of the Fourdrinier part during the replacement of the wire;

Fig. 3 is a top plan view of the structure of Fig. 1;

Fig. 4 is an enlarged side elevational view 55 of the breast-roll end of a paper-making machine;

Fig. 5 is a similar view, but showing the couch-roll end;

Fig. 6 is a transverse sectional view taken 60 on the line 6—6 of Fig. 5;

Figs. 7, 8, and 9 are similar views taken on the line 7—7, 8—8 and 9—9, respectively, of Fig. 1;

Fig. 10 is a detail transverse sectional view 65 taken on the line 10—10 of Fig. 5; and

Fig. 11 is a top plan view of one of the gear boxes with the cover removed.

Referring to the drawing, the paper-making machine therein disclosed comprises broadly a head-box 1 having a so called "Voith inlet" 2 positioned to discharge onto a breast-roll end 3 of a wire 4 supported by a removable Fourdrinier part 5, the pulp being finally transferred from a couch-roll 75 end 6 of the wire 4 to the usual drying rolls (not shown).

The Fourdrinier part 5, which embodies the principal features of my invention, comprises a removable table-roll section 7, and independently removable contiguous suction-box section 8, and a suction or couch roll 9 bodily movable on ways 11 extending longitudinally of the wire 4.

Considering the table-roll section 7 in greater detail, a pair of longitudinally extending side table rails 12 and 13 are provided with bearings 14 for the support of the usual table rolls 15. The rolls 15 together constitute an upper working surface 16 providing a support for the Fourdrinier wire 4. According to my invention, a rear or couch-roll end 17 of the rails 12 and 13 has pivotal mountings 18 and 19 which are respectively supported on adjacent rear ends 21 of side portions 22 and 23 of a supporting frame 24.

Each of the mountings or bearings 18, 19 comprises a vertical trunnion pin 25 which extends upwardly through the adjacent table rail from a horizontal bearing surface 26. 100

- The rail-supporting surface 26 is formed on an upper side 27 of a longitudinally extending member constituting one of the side frame portions 22, 23. The vertical trunnion pin 25 and the bearing surface 26 thus permit a limited horizontal vibratory movement of the table rails 12, 13, and rolls 15,—this movement being substantially negligible at the couch-roll end 17, but a maximum at the breast roll end 3 of the Fourdrinier wire.
- 10 The side portion 22 of the supporting frame 24 comprises rear and front box-like end sections 28 and 29 respectively, upper sides 31 of which are interconnected by an angle 32 positioned directly beneath but in spaced relation to the adjacent table or shake rail 12. The angle 32 at spaced points intermediate the ends thereof is provided with downwardly extending angle sections 33 and 34 which are secured to a reinforcing angle 35 having a horizontal section 36 positioned intermediate the depending sections 33 and 34 and end sections 37 and 38 respectively extending upwardly to the adjacent sides of the box-like sections 29 and 28. The opposite side portion 23 embodies similar horizontal and vertical reinforcing angles 39 and 41 and enlarged rear and front end sections 42 and 43. The rear box sections 28 and 42 are interconnected by an angle 44, while the front box sections 29 and 43 are interconnected by an angle 45. The lower ends of the vertical angles 33, 41 and 34 may be connected by transverse angles 46 and 47 respectively.
- 15 The table rails 12 and 13 are interconnected adjacent to the vertical angles 34 and 41 by a shaft 48, each end of which is provided with a pin 49 which extends upwardly through the adjacent rail and terminates in a supporting head 51 in the form of a supporting bolt head or nut, a similarly supported shaft 50 extends between the vertical angles 33 and 41.
- As shown in Fig. 8 the portion of the rails 12 and 13 respectively adjacent to the vertical angles 34 and 41 may be supported by a pair of resilient devices 52 permitting lateral vibratory movement about the pivotal mountings 18 and 19. Each of the devices 52 comprises a pair of spring strips 53, the upper ends of which are bolted to flanges 54 extending from opposite sides of the shaft 48. The lower ends of the strips 53 are mounted on flange 55 extending from opposite sides of the transverse angle 47. The portions of the shake rails 12 and 13 adjacent to the vertical angles 33 and 41 respectively are similarly supported for lateral vibration by means of resilient devices 56, 57.
- 20 The table rails 12 and 13 may be further supported adjacent to the breast roll end 3 of the wire 4 to afford the desired lateral vibratory movement by means of a pair of pedestals 58 and 59, respectively. These pedestals extend upwardly from a supporting floor surface 59 to bearings 61 and 62 respectively secured to adjacent flanged ends 63 of the shake rails 12 and 13. The bearings 61 and 62 serve to support shaft 64 carrying a breast roll 65 around which the wire extends.
- 25 As illustrated in Fig. 9 each of the pedestals 57, 58, comprises a base 66, a block 67 which is removable secured thereto by bolts 68, and a spring structure 69. The structure 69 includes a pair of spaced strips 71, the lower ends of which are secured to opposite sides of a bracket member 72 secured by bolts 73 to the removable block 67. The upper ends of the spring strips 71 are spaced by a member 74 pivotally mounted thereon by pins 75. The member 74 is provided with a central recess for the reception of a tongue 76 extending downwardly from the adjacent bearing. These parts may be pivotally connected together by a pin 75. Such mounting permits the breast roll 65 and connected shake rails 12 and 13 to move in a vertical plane about the spring structure 69 without interfering with the lateral vibratory movement thereof. It will be noted that the pedestals 57, 58 serve to support the breast roll 65 and adjacent ends of the shake rails 12 and 13 independently of the main supporting frame 24, the latter in turn supporting the intermediate resilient devices 52 and 56, 56 as well as the vertical pivotal mountings 18 and 19 at the couch-roll end 17.
- 30 My invention also contemplates the hinging of the frame 24, whereby the couch-roll end 17 may be moved vertically to adjust the pitch of the wire 4. To this end, a pair of supporting pedestals 78 and 79 are positioned directly below the front box sections 29 and 43. Each pedestal 78, 79 comprise a bracket 81 extending upwardly from the base 66 and a removable bearing block 82 embodying the lower half 83 of a pivotal bearing 84, an upper half 85 of which is formed on a bracket 86 secured to an underside 87 of the box section 29, 43. The bearing parts 83 and 85 embrace a pivot pin 88.
- 35 Such vertical adjustment of the frame 24 about the pivotal bearings 84, 84 as may be necessary to establish the desired pitch of the wire 4 may be effected at the couch-roll end 17 by power means 89. The power means 89 comprise a pair of spaced screw-jack devices 91 and 92 positioned directly beneath the rear box sections 28 and 42, respectively, on the floor surface 59. The devices 91 and 92 are interconnected by a common cross shaft 93 extending to a gear box 94 having a control element 95. The gear box 94 is connected to a main operating shaft 96 extending longitudinally of the Fourdrinier part 5. The main power shaft 93 is driven by a motor 97. As shown, the gear box 94 is so constructed that when the control element 95 is in one position, the cross shaft 93 is connected to the main power shaft 96 to operate the screw jacks 91 and 92 in one direction. When the contact element 95 is 130

- 5 moved into another position, the screw jacks 91 and 92 are operated in the reverse direction of movement into an intermediate position however serving to disconnect the cross shaft 93 from the main operating shaft 96.
- 10 5 Each of the screw-jack devices 91, 92 comprises a post 98, a lower end of which carries a wheel 99 which meshes with a worm 101 on the cross shaft 93. The post 98 may be guided by means of a casing 102 for movement into and out of engagement with a spherical recess 103 formed in the lower end of a block 104 mounted on the underside of the rear box sections 28, 42. The upper end of the post 98 is formed with a surface complementary 15 to that of the recess 103. When it is desired to adjust the pitch of the table rails 12 and 13, the control element 95 is moved into the position causing the desired vertical movement of the post 98 and hence the frame 24 about the pivotal mountings 84.
- 20 My invention still further contemplates the lowering of the table-roll section 7 from the upper working position of Fig. 1 to the 25 lower position of Fig. 2 wherein the frame 24 and associated parts may be removed from the machine to permit the replacement of a damaged or worn out wire. Accordingly, I provide power means 105 at the hinged front 30 end of the frame 24, said power means constituting supports auxiliary to the bearings 84, 84, permitting the removal of the blocks 67 and 82 and, thereafter, in combination, with the power means 89, the lowering of the 35 structure 24 into the desired position, as will presently appear. The power means 105 comprises a pair of screw-jack devices 106 and 107 corresponding to the devices 91 and 92. Each of the devices 106, 107 includes a vertically movable post 108, the upper end of 40 which is movable into engagement with the bearing bracket 86, while a lower end is provided with a wheel 109 in mesh with a worm 111 on a cross shaft 112. The shaft 112 is connected to a gear box 113 corresponding to the gear box 94. The gear box 113 is provided with a control element 114 having raising, lowering and neutral positions, as in the case of the control elements 95.
- 45 50 The posts 108 may be inclosed in a housing 115 which forms a part of the pedestals 78 and 79. The housings 115 are provided with aligned recesses 116 for the reception of removable I-beam rails 117 that 55 extend transversely of the machine into the side aisle. The casing 102 for the screw-jack devices 91 and 92 is also provided with aligned recesses 118 for the reception of removable rails 119 extending into the side 60 aisle of the machine. The movement of the frame 24 over these rails may be facilitated by wheels 121, of which four are shown, two being respectively mounted on the side frame portions 22 and 23 adjacent to the 65 breast roll 65 and the remaining two being similarly mounted at the rear end of the frame 24. The wheels 121 may be partially enclosed by a protective casing 123.
- 70 Assuming that the wire 4 is slack and that the bolts securing the removable blocks 67 and 82 are removed, the first step in the removal of the table-roll section 7 is the actuation of the control element 114 into its raising position. As a result the posts 108 move upwardly into engagement with the bearing brackets 86, assuming the load carried by 75 the frame-supporting pedestals 78 and 79. The further vertical movement of the posts 108 cause adjustable frame abutments to engage the flanged ends 63 of the shake rails 12 and 13, respectively, causing the load carried by the breast-roll pedestals 57 and 58 to be transferred to the posts 108. The front and rear posts 108 and 98 now support the frame 24, the breast-roll 65, table rolls 15 and rails 12 and 13, permitting the blocks 80 85 67 and 82 to be removed.
- 80 The control elements 95 and 114 are now moved into their lowering position, with the result that the posts 108 and 109 move downwardly, dropping the table section 7 from its upper working position to its lower position wherein the wheels 121 engage the rails 117 and 118. The table section 7 may now be moved laterally of the machine into the side aisle. Such movement occurs independently 90 of the suction-box section 8.
- 95 The suction-box section 8 has a rear end 125 thereof pivotally mounted on bearings 126 provided by spaced pedestals 127 respectively, positioned at the opposite sides of the section. Each of the pedestals 127 includes a removable bearing block 128 corresponding to the removable blocks 82 associated with the pedestals 78 and 79 in the table section 7. A front end 129 of the suction-box section 8, which is adjacent to the rear end 17 of the table rails 12 and 13, is supported on power means 131 comprising screw-jack devices 132 identical with those for the table-section 7. The devices 132 are interconnected by a common shaft 133 leading to a gear box 134 having an operating element 135 for controlling the connection 100 between the shaft 133 and the main-operating 105 shaft 92.
- 110 Should it be desirable to change the pitch of the wire 4 independently of or in conjunction with the table section 7, the control element 135 is operated into its raising position, wherein the main shaft 96 is connected to cause the devices 132 to move vertically the front end 129 of the suction-box 115 120 8. Such movement occurs about the pivotal bearings 126. Additional power means 136 corresponding to the table power means 105 may be provided adjacent to the pedestals 127, and it comprises a pair of screw-jack devices 137 having an inter-connected power 125 130

shaft 138 extending to a gear box 139 controlled by an element 141.

The front and rear screw-jack devices 132 and 137 have recesses 142 in their casings for the removable reception of front and rear rails 143 and 144 adapted to co-operate with wheels 145 carried by the suction-box section 8. When it is desired to remove the section 8, the control element 141 is moved 10 into its raising position, causing the rear screw-jack devices 137 to lift the suction-box end 125 from the bearing pedestals 127, whereupon the blocks 128 may be removed. The control elements 135 and 141 are then 15 actuated into their lowering position, permitting the screw-jack devices 132 and 137 to lower the suction-box section 8 from its upper working position to a lower position wherein the wheels 145 engage the rails 20 143 and 144. The suction-box section 8 may now be removed from the machine into the side aisle.

A still further feature of my invention is the provision of means, whereby the suction roll 9 may be moved upon power backward from the running position to give slack to the wire 4. As shown in Figs. 1, 2 and 3, such construction involves the mounting of the opposite ends of a couch-roll shaft 146 30 on bearing pedestals 147 and 148 which are respectively supported on the ways 11 extending longitudinally of the machine. Each of the ways 11 is provided with a central recess for a screw shaft 149, one end of 35 which extends into a correspondingly threaded portion of the pedestals 147, 148. An opposite end of the screw shaft 149 is geared to a transversely extending shaft 151 which terminates in a gear box 152 having a control element 153. The gear box 152 is connected to the main operating shaft 96, as in the preceding gear boxes, and it is of similar design. When the element 153 is actuated into one position, the pedestals 40 45 147 and couch-roll 9 are actuated to slacken the wire 4, but when said element is oppositely actuated, the couch roll 9 is moved to tighten the wire 4.

Assuming the table-roll section 7 and the 50 suction-box section 8 in their laterally removed positions in the machine aisle and the suction roll 9 moved back, affording a maximum slack in the wire 4, the Fourdrinier part is in the position permitting the removal and replacement of the wire 4. When a new wire 4 is positioned in the machine, the table-roll and suction-box sections 7 and 8 are moved on their supporting rails into 55 longitudinal alignment with the adjacent 60 machine parts. The gear box control elements 95 and 114 for the table-roll section 7 are now actuated to cause the main operating shaft 25 to raise the pedestals 98 and 108 until the pedestal blocks 67 and 82 may 65 be replaced. The front control element 114

is then reversely operated to cause the front posts 108 to move downwardly, permitting the load of the breast-roll 65 and adjacent table-rolls 12 and 13 to be transferred to the pedestals 57, 58, and the load of the front end of the frame 24 to be assumed by the bearing pedestals 78, 79. The suction box section 8 is similarly returned to its original position shown in Fig. 1, and the suction roll 9 is then moved forward by the power shaft 96 through the gear box 152 to running position. The pitch of the wire 4 is next adjusted by the posts 98 or 131 or both.

While I have shown only one form of embodiment of my invention, for the purpose of describing the same and illustrating its principles of construction and of operation, it is apparent that various changes and modifications may be made therein without departing from the spirit of my invention, and I desire, therefore, that only such limitations shall be imposed thereon as are indicated in the appended claims or demanded by the prior art.

I claim:

1. A Fourdrinier machine comprising independently removable table-roll and suction-box sections.
2. A paper making machine having a couch roll, and means for bodily moving said roll longitudinally of the machine.
3. A Fourdrinier machine having a suction box section that is removable as a unit independently of the rest of the machine.
4. A Fourdrinier machine having independently removable sections, a wire supporting couch roll, and power means for longitudinally shifting the position of the said roll with respect to the said sections.
5. A Fourdrinier machine having independently removable sections and a wire supporting suction roll movable independently thereof.
6. A Fourdrinier machine having independently removable table-roll and suction-box sections, and a wire supporting couch roll movable longitudinally with respect to the said suction-box section.
7. A Fourdrinier machine having a table-roll and suction-box sections, the said sections being independently removable with respect to each other, a breast roll carried rigidly by the table-roll section, a single couch roll movable independently of the suction-box section, and a wire movable over said sections and supported at one end by the said breast roll and at the other end by the said couch roll.
8. A removable Fourdrinier part comprising a bodily movable table-roll section and a suction-box section, said sections being independently removable, a breast roll carried by one of said sections and a couch-roll movable independently of the other section.
9. In combination, a Fourdrinier part com-

- prising independent table-roll and suction-box sections, a wire passing over said sections having inlet and discharge ends, a breast roll for supporting the inlet end of said wire, and a roll positioned to move independently 5 of said sections for supporting the discharge end of said wire.
10. A paper-making machine comprising removable table-roll and suction-box sections, a wire passing over said sections, a breast-roll carried by said table-roll section for supporting one end of said wire, a roll supporting the other end of said wire, and means whereby one of said rolls may be moved relative to the other to vary the tension of the 15 wire.
11. A Fourdrinier machine comprising a wire-supporting structure including independently removable table-roll and suction-box sections, means whereby said sections 20 may be independently lowered to a desired position, and means permitting the removal of said sections while in their lowered position.
12. A Fourdrinier machine having, in combination, a plurality of independently removable wire-supporting sections, a wire movable over said sections, and common power means for independently moving said sections from an elevated working position to 25 a lowered removing position.
13. A plurality of sections adapted to co-operate with a Fourdrinier wire, said sections having an elevated working position and a lowered position, means whereby said sections may be removed while in their lowered positions, and a couch roll movable longitudinally of said sections.
14. Apparatus of the class described comprising a wire, a roll for supporting the discharge end of said wire, movable longitudinally thereof, a sectional Fourdrinier part 35 movable from an elevated working position to a lower position, and power means for moving said sections from one of said positions to the other, said power means also being connected to said roll.
15. A machine comprising a wire, a plurality of sections co-operating therewith, a breast roll carried by one of said sections, a couch roll positioned adjacent to the other section and movable longitudinally of said wire, said sections being movable from an upper working position to a lower position, and means whereby said sections may be 45 dropped to said last-mentioned position and removed from said machine.
16. In combination, a wire, a plurality of sections co-operating therewith, a breast roll 50 carried by one of said sections, a couch roll positioned adjacent to the other section and movable longitudinally thereof, said sections being movable from an upper working position to a lower position, power means for dropping said sections from said raised position to 55 said lower position, and means whereby said sections may be moved away from said couch roll while in said lowered position.
17. In a Fourdrinier machine, a wire, a sectional structure having an upper working position in operative relation to said wire, said sections having a lower position, common power means for actuating said sections from one position to the other, a breast roll carried by one of said sections, a couch roll movable longitudinally of said wire and adapted to be connected to said power means, and means whereby said sections may be removed from said machine.
18. A Fourdrinier machine comprising a sectional structure adapted to co-operate with a wire and having an upper working position, a breast roll connected to one of said sections, a bodily movable suction roll, common power means for actuating said suction roll and for lowering said sections to a desired position, and means permitting the removal of said sections while in said lowered position.
19. In a Fourdrinier machine, table-roll and suction-box sections having an elevated working position, power means for dropping said sections to a lowered position, and means whereby said sections may be independently removed while in said lowered position.
20. A Fourdrinier machine comprising table-roll and suction-box sections having an elevated working position, a breast roll connected to said table-roll section, a couch roll movable longitudinally of said suction-box section, common power means for dropping said sections to a lower position and for actuating said couch roll, and means whereby said sections may be independently removed while in said lower position.
21. The combination with table-roll and suction-box sections, of a breast roll connected to said table-roll section, a couch roll movable longitudinally of said table-roll section, common power means for lowering said sections from an elevated working position to a desired lowered position, and means whereby said sections may be removed, said power means having control mechanism permitting the independent actuation of said sections.
22. In combination, a table-roll section, a suction-box section, a breast roll secured to said table-roll section, a couch roll movable longitudinally of said suction-box section, said sections having an elevated working position, power means for dropping said sections to a predetermined lowered position and for also moving said couch roll, and means whereby said sections may be moved away from said couch roll while in said lowered position, said power means including control mechanism permitting the independent actuation of said sections and said couch roll.
23. A Fourdrinier machine having inde-

pendently removable table-roll and suction-box sections, the extreme ends of said sections being mounted on removable pivots.

24. A Fourdrinier machine including a wire, independently removable table-roll and suction-box sections positioned in co-operative relation to said wire, and means whereby a movement may be imparted to at least one of said sections, so that the pitch of said wire may be adjusted.

25. A Fourdrinier machine including a wire, independently removable table-roll and suction-box sections positioned in co-operative relation to said wire, the opposite ends of said sections being mounted on removable pivots, and means whereby said sections can be adjusted to impart a desired pitch to the wire.

26. In a Fourdrinier machine, the combination with a plurality of independently removable table and suction box sections adapted to cooperate with a wire, of supporting means for said sections affording an adjustment in the wire pitch intermediate the ends of said wire.

27. A Fourdrinier part comprising a pair of contiguous sections, means for pivotally mounting corresponding ends of said sections, means for supporting the remaining ends of said sections, and supporting means supplementary to said first-mentioned means, said last-mentioned supporting means and said second-mentioned means permitting the lowering of said sections from an upper working position to a lower position wherein said sections may be removed.

28. A Fourdrinier machine comprising a sectional part having an upper working position adapted to co-operate with a wire, and a lower position, means affording corresponding ends of said sections, a hinged mounting power means associated with the remaining ends, whereby the pitch of said wire may be adjusted, and additional power means constituting supports auxiliary to said first-mentioned means, said additional power means and said second-mentioned means being operable to drop said sections to said lower position, and means whereby said sections may be removed from said machine while in said lower position.

29. A paper machine comprising contiguous sections having an upper working position, a wire movable over said sections, a breast roll connected to one of said sections, a couch roll movable longitudinally of said wire disposed adjacent to the other section, means for pivotally mounting said sections, power means operative on at least one of said sections to cause variations in the pitch of said wire, and additional power means providing supports auxiliary to said first-mentioned means, said auxiliary supports and said second-mentioned means permitting the dropping of said sections to a predetermined

lowered position, and means whereby said sections may be removed from said machine while in said lowered position.

30. A Fourdrinier machine comprising independently removable table-roll and suction-box sections, a breast roll, a couch roll, a wire movable over said parts, means affording said sections a hinged mounting, means whereby the pitch of said wire may be adjusted, and supporting means auxiliary to said first-mentioned means, said auxiliary supporting means and said second-mentioned means permitting the dropping of said sections to a pre-determined lower position wherein the same may be independently removed from said machine.

31. A paper-making machine comprising a table-roll section having a breast roll mounted on one end, a suction-box section, a bodily movable couch roll, means for pivotally mounting opposite ends of said sections, supporting means for adjacent ends of said sections affording variations in the pitch of at least one of said sections, supporting means auxiliary to said first-mentioned means, said auxiliary supporting means and said second-mentioned means permitting the dropping of said sections to a predetermined position wherein the same may be removed from said machine, and common actuating means for said auxiliary supporting means and said second-mentioned means.

32. A Fourdrinier machine comprising a table-roll section, a breast roll mounted on one end thereof, a suction-box section, a couch roll movable longitudinally of one of said sections, means for pivotally mounting corresponding ends of said sections, supporting means for the remaining ends of said sections affording variations in the pitch of at least one of said sections, supporting means auxiliary to said first-mentioned means, said auxiliary supporting means and said second-mentioned means permitting a movement of said sections to a predetermined position wherein the same may be removed from said machine, and common actuating means for said auxiliary supporting means, said second-mentioned means and said couch roll.

33. In a paper-making machine, the combination with a table-roll section, a breast roll operatively associated therewith, a suction box section, a bodily movable couch roll, and a wire, of means for pivotally mounting the opposite ends of said sections, supporting means for the adjacent ends of said sections affording variations in the pitch of said wire, auxiliary supporting means adapted to replace said first-mentioned means, said auxiliary supporting means and said second-mentioned means permitting a movement of said sections to a predetermined position wherein the same may be removed from said machine, common actuating means for said auxiliary

supporting means and said second-mentioned means, and control means for said common actuating means individual to said sections.

34. A machine comprising a table-roll section, a suction box section, a bodily movable couch roll, a wire, means for pivotally mounting the opposite ends of said sections, supporting means for the adjacent ends of said sections affording variations in the pitch of said wire, auxiliary supporting means adapted to replace said first-mentioned means, said auxiliary supporting means and said second-mentioned means permitting the dropping of said sections to a predetermined position wherein the same may be removed from said machine, actuating means for said auxiliary supporting means, said second-mentioned means, and said couch roll and control means for said actuating means individual to said sections and said couch roll.

35. A removable Fourdrinier part, a co-operating wire, a base, removable means positioned intermediate said base and said part affording the latter pivotal mounting, means for moving said part about said pivotal mounting, auxiliary supporting means permitting the removal of said first-mentioned means, said auxiliary means and said second-mentioned means being adapted to lower said part from an elevated working position, and means whereby said part may be moved in a different direction from said lowered position.

36. A machine of the class described comprising a Fourdrinier part, support means affording said part a pivotal mounting, said means including a removable element, power means for actuating said part about said mounting to vary the pitch thereof, means whereby said part may be removed from said machine and auxiliary supporting means permitting the removal of said element and thereafter in combination with said second-mentioned means the dropping of said Fourdrinier part from an upper working position into operative relation to said third-mentioned means.

37. In a paper-making machine, a suction-box frame, a base having a removable part affording a pivotal mounting to one end thereof, power means for actuating said frame about said mounting, means whereby said frame may be moved from said machine, and auxiliary supporting means permitting the removal of said part and thereafter in combination with said first-mentioned means the lowering of said frame into engagement with said second-mentioned means.

38. A Fourdrinier part, supporting means affording said part a pivotal mounting, said means including a removable element, a power-operated post for moving said part about said mounting to vary the pitch thereof, and a second power-operated post con-

stituting a support auxiliary to said supporting means.

39. A Fourdrinier section adapted to co-operate with a wire, a pedestal having a removable part affording said section a pivotal mounting, a power-operated post positioned to actuate said section about said mounting, and a second power operated post constituting a support auxiliary to said removable part.

40. In combination, a suction-box section, a pedestal affording one end of said section a pivotal mounting and including a removable part, a power-operated post for moving said section about said mounting, and a second power-operated post constituting a support auxiliary to said pivotal mounting.

41. In combination, a suction-box frame, a pedestal having a removable part affording one end of said frame, a pivotal mounting, a power-operated post for moving said frame about said mounting, a second power-operated post constituting a support auxiliary to said pivotal mounting, and common operating means for said posts.

42. A frame adapted to support a suction box, a pedestal having a removable part affording one end of said frame a pivotal mounting, a power-operated post for moving said frame about a mounting, a second power-operated post constituting a support auxiliary to said pivotal mounting, and common operating means for said posts, the latter being independently controlled.

43. In a Fourdrinier machine, a frame adapted to support a suction box, a base having a removable part affording said frame a pivotal mounting, a power-operated post for actuating said frame about said mounting, means whereby said frame may be moved away from said post, and a second post permitting said pivotal mounting to be rendered ineffective and thereafter in combination with said first-mentioned post the dropping of said frame from an upper working position into engagement with said means.

44. A paper-making machine comprising a table-roll section, a base affording a pivotal mounting to the breast-roll end of said section, said base having a power-operated post for actuating said section about said mounting, means whereby said section may be actuated from said machine while in a predetermined lowered position, and a second post operative to permit said pivotal mounting to be rendered ineffective by the removal of said part and thereafter in combination with said first-mentioned post the lowering of said section into operative relation to said means.

45. A paper-making machine comprising a table-roll section, a base having a removable part affording a pivotal mounting to the breast-roll end of said section, a power-operated post for actuating said section about said

- mounting, means whereby said section may be actuated from said machine while in a predetermined lowered position, a second post operative to permit said pivotal mounting to be rendered ineffective and thereafter in combination with said first-mentioned post the lowering of said table-roll section into operative relation to said means, and common means for operating said posts.
46. A paper-making machine comprising a table-roll section, a base affording a pivotal mounting to the breast-roll end of said section, a removable part and base having a power-operated post for actuating said section about said mounting, means whereby said section may be actuated from said machine while in a predetermined lowered position, a second post operative to permit said pivotal mounting to be rendered ineffective and thereafter in combination with said first-mentioned post the lowering of said table-roll section into operative relation to said means, common means for operating said posts, and individual control means for said posts.
47. In a machine of the class described, a Fourdrinier part comprising table rails, a bodily movable structure adapted to provide said rails a pivotal mounting, additional supporting means for said rails permitting the vibration thereof, means whereby said structure may be removed from said machine while in a position other than its normal working position, and power means for actuating said rails and supporting structure to said first-mentioned position.
48. In a removable Fourdrinier machine, table rails, a breast roll secured to said table rails, means for providing said table rails a pivotal support, and additional supporting means for said rails permitting a movement about said pivotal support, said first-mentioned means including means whereby the pitch of the said rails may be adjusted.
49. In combination, in a Fourdrinier machine having a removable table, table rails, a breast roll mounted thereon, supporting means affording said rails a pivotal mounting, supporting means for said breast roll permitting a movement of said rails about said mounting, said first-mentioned means including power means whereby the pitch of said rails may be adjusted, and additional power means for vertically moving the breast roll end of said rails.
50. A table rail, a supporting structure affording said rail a pivotal mounting, a breast roll secured to said rail, supporting means for said roll permitting a movement thereof about said pivotal mounting, means for providing a hinged support for said supporting structure, power means for moving said structure about said hinged support, means permitting said table to be removed from said machine, and additional power operating means adapted in combination with
- said first-mentioned power means to drop said structure into operative relation to said fourth-mentioned means.
51. In combination with a removable Fourdrinier machine, table rails having a pivotal mounting at the discharge end, a breast roll secured to the other end, and supporting means for the breast roll end of said rails permitting the same to be vibrated laterally and also moved vertically at said discharge end.
52. In a removable Fourdrinier machine, a table rail having a discharge end thereof provided with a pivotal mounting, a breast roll mounted on the other end thereof, and supporting means for said breast roll end of said rail permitting a lateral movement of said rail about said pivotal mounting and also a vertical movement at said discharge end, said means including a removable part, whereby said breast roll end may be dropped to a desired extent.
53. In a machine of the class described, a table rail having a discharge end, a hinged structure affording said rail a pivotal mounting at the discharge end thereof, a breast roll secured to the opposite end of said rail, supporting means for said breast roll permitting a movement about said pivotal mounting and also a movement due to the swinging of said hinged structure, a movable suction-box section, and a couch roll movable longitudinally of said section.
54. In a removable Fourdrinier machine, a table rail, a supporting structure affording said rail a pivotal mounting, a removable bearing affording said structure a hinged mounting, means permitting a movement of said table rail due to said mountings including a removable part, means permitting said table rails to be removed from said machine and power means for dropping said rail from an upper working position to a lower position in proximity to said second-mentioned means.
55. In a Fourdrinier machine, a pair of table rails having a discharge end, a supporting structure having one end thereof provided with a bearing affording said discharge end of the rails a pivotal mounting, means for providing a hinged mounting for the other end of said structure including a removable part, a breast roll secured to said table rails, supporting means for said breast roll permitting movements of said rails about both mountings, said last-mentioned means including a spring member and a removable part, a power-operated post for actuating said supporting structure about its mounting in order to adjust the pitch of the table rails, means for permitting the removal of said supporting structure, table rails and breast roll from said machine, and additional power means constituting supports auxiliary to said first-mentioned supporting means and serving in combination with said

first-mentioned power means upon the removal of said removable parts to permit the lowering of said supporting structure into engagement with said third-mentioned means.

5 56. In a removable Fourdrinier machine, in combination, a pivotally mounted suction box section having power operating means for raising and lowering the same, and a couch roll having power operating means for 10 moving the same longitudinally thereof.

57. A table roll supporting element having a discharge end, a breast roll mounted on one end of said element, a spring support 15 for said breast roll, a bodily removable supporting frame affording said element a pivotal mounting, said frame being pivoted adjacent to said breast roll, and means for vertically adjusting said frame and element 20 adjacent to the discharge end of the latter.

58. In a paper-making machine, laterally removable table and suction box sections, and a plurality of power operated posts positioned below said sections for lowering the 25 same either simultaneously or independently into a position permitting said lateral movement.

59. A Fourdrinier machine comprising 30 table-roll and suction-box sections, with vertically adjustable means for supporting said sections, the said supporting means at the ends of the machine having removable pivotal connections with the said sections.

35 60. A Fourdrinier machine having vertically adjustable supporting means, the said supporting means at the ends of the machine having detachable pivotal connection therewith.

40 GEORGE D. KILBERRY.
